UNITED STATES PATENT OFFICE.

CURTIS A. TUCKER, OF EDGEWOOD PARK, PENNSYLVANIA, ASSIGNEE TO WESTINGHOUSE ELECTRIC AND MANUFACTURING COMPANY, A CORPORATION OF PENNSYLVANIA.

CIRCUIT-BREAKER.

1,151,739.

Specification of Letters Patent. Patented Aug. 31, 1915.

Application filed December 28, 1909. Serial No. 535,437.

To all whom it may concern:

Be it known that I, CURTIS A. TUCKER, a citizen of the United States, and a resident of Edgewood Park, in the county of Allegheny and State of Pennsylvania, have invented a new and useful Improvement in Circuit-Breakers, of which the following is a specification.

My invention relates to electric circuit switching devices and particularly to such automatic circuit interrupters as are adapted for very large-current service.

One of the objects of my invention is to provide a device of the class above indicated that shall be simple and compact in construction and which, at the same time, may be closed manually with a relatively slight exertion and be capable of transmitting several thousand amperes.

Another object of my invention is to provide an improved and effective means for insuring that the main and auxiliary contact members become engaged and separated in a predetermined sequence, that the movable contact members are well removed from their coöperating stationary members prior to the final interruption of the circuit at the auxiliary arcing terminals, and also for resiliently transmitting the movement of the main contact bearing arm to the auxiliary supporting member and for maintaining the auxiliary arcing terminals under pressure in their closed position.

The movable contact members of circuit breakers designed for large-current services are very heavy, and, if the usual toggle mechanism is employed between the operating lever and said member, large forces must be applied in order to close the breaker unless the operating lever is made very long and the parts of the mechanism very strong.

According to my present invention, I employ a cam mechanism in addition to the usual toggle mechanism, the arrangement of parts being such that a relatively small force exerted on an operating lever of ordinary length will close the breaker. Furthermore, I provide two independent supporting arms for the main and auxiliary contact members, which are eccentrically pivotally mounted upon the frame and are mechanically associated for coöperative operation by a lost-motion resilient connection.

Figure 1 of the accompanying drawings is a side elevation of a circuit interrupter 55 constructed in accordance with my invention, the parts being shown in closed-circuit position. Fig. 2 is a view similar to that of Fig. 1 except that the parts are shown in open-circuit position. Fig. 3 is a front elevation of the breaker shown in the other figures, and Fig. 4 is a detail view of a portion of the operating mechanism.

Referring to the drawings, the circuit interrupter here shown comprises stationary 65 contact members 1 and 2 which are mounted on a slab or base 3 of insulating material, a movable contact member 4 which is adapted to bridge the stationary contact members when the breaker is closed, an operating lever 5 and an operating mechanism 6.

The stationary contact member 1 is provided with auxiliary contact members 7, preferably of carbon, which are supported by a bracket 8 and are adapted to take the 75 arc formed when the circuit is interrupted.

The movable contact member 4 comprises a plurality of laminated contact members assembled side by side and attached to a series of brackets 8^a which are pivotally 80 mounted on a rod or shaft 9.

The operating mechanism 6 comprises a pair of duplicate cams 10 which are pivotally supported on short rods or pins 11 that project inwardly from the two arms of the 85 usual stationary bracket 12 secured to the slab or base 3, a pair of curved levers 13 which are each pivotally supported upon the ends of a shaft 14 and are each pivotally connected to one extremity of one of the 90 cams 10; a contact bearing member 15, which is pivotally mounted on a stationary shaft 16 which is carried by the brackets 12 and on which the shaft 14 is supported, and the operating lever 5. The lever 5 is 95 composed of two arms 5^a which are pivotally supported on the shaft 16, and are provided with rollers 17 to engage the outer edge surfaces of the cams 10, and are joined together at their outer ends by insulating handle 100 grips 5^b. The contact bearing member 15 is provided with a rod or shaft 18 on which a series of levers 19 are fulcrumed, these levers being pivotally connected to the brackets 8^a to which the segments of the contact 105 member 4 are secured.

Springs 20 are mounted on guide pins 21 and are disposed between the lower ends of the levers 19 and ledges 22 on the member 15 to which they are secured at one end. The arrangement of parts is such that the 5 springs tend to force the lower ends of the levers 19 outwardly and thereby throw the contact members inwardly and form, by reason of their resiliency, a set of yielding connections which maintain excellent contact between the sections of the movable contact members 4 and the stationary members 1 and 2.

A bracket 23 depends from the contact-bearing member 15 and is provided with a 15 release magnet 24 which is adapted to rotate a latch 25 in opposition to a spring 26 and to trip the circuit breaker in the usual manner. The latch 25 is provided with a lock 20 at its outer end to engage a roller 27 located on a shaft which connects the outer ends of the cams 10.

A bifurcated auxiliary contact-bearing member 28 is pivotally supported from the 25 brackets 12 by pins 29 and is provided with arcing contact blocks 30 which coöperate with the members 7. The pins 29 and the shaft 16 are disposed substantially one above the other. The members 7 and 30 are forced 30 into engagement with each other by means of coil compression springs 31 mounted on slidably and pivotally mounted guide pins 32 and disposed between intermediate points 33 in the arms of the member 28, to which 35 the pins 32 are fulcrumed and pivotally connected, and the upper ends of the contact-bearing member 15 with which the outer ends of the pins have sliding and pivotal connections.

40 The operation of the device is as follows: Assuming that the parts occupy the positions shown in Fig. 1 of the drawings, if the release magnet 24 is energized, a hammer rod 34 strikes one end of the latch 25 and 45 withdraws the outer end of the latch from the roller 27. The resiliency of the movable contact members 4 and the compressed springs 20 and 31 are sufficient to initially separate the contact members as soon as the 50 latch is released, and the weight of the parts will then throw the breaker to its open position, as illustrated in Fig. 2.

If it is desired to close the interrupter, assuming that the parts occupy positions 55 shown in Fig. 2, downward pressure is applied to the lever 5 which rotates about the shaft 16 as an axis. The rollers 17 travel along the surfaces of the cams 10 which cause them to rotate about the pins 11. This 60 action rotates the levers 13 about the shaft 14 as an axis and decreases the distance of separation between the shafts 11 and 14. Since the member 15 is pivoted upon the stationary shaft 16 as an axis and since the 65 shaft 11 is stationary, the shaft 14 must

approach the shaft 11, and, consequently, the member 15 must rotate in a counter-clockwise direction and thus throw the contact members 4 into engagement with the stationary contact members 1 and 2.

The pivotal supports and fulcrum points of the contact supporting member 15 and the auxiliary contact-bearing lever 28 are so placed and the resilient lost-motion connection between them is so constructed that the 70 arcing contact members 7 and 30 come into engagement with each other before the primary contact members come into engagement and, therefore, they are separated last in opening the breaker and no arcs are established between the main contact members.

The lever 5 is provided with springs 36 which tend to rotate it in a counter-clockwise direction and hold it in the position shown in Fig. 1 when the breaker is closed.

The form and structure of the circuit breaker may obviously be modified within the scope of my invention, and I desire that only such limitations shall be imposed as are indicated in the appended claims.

I claim as my invention:

1. In a circuit interrupter, the combination with stationary and movable contact members and an operating lever, of an operating mechanism interposed between the operating lever and the movable contact member, said mechanism comprising a pivotally supported contact-bearing member, a link and lever connection between an intermediate point therein and a stationary pivot 95 for the lever, the lever having a cam surface, and a roller secured to an intermediate point in the operating lever to coöperate with the surface of said cam.

2. In a circuit interrupter, the combination with stationary and movable contact members and an operating lever having two parallel arms joined near their outer ends, of an operating mechanism for connecting the operating lever to the movable contact member comprising a pair of relatively stationary shafts, a contact-bearing member pivotally mounted on one of said shafts and connected to the other by a toggle joint connection consisting of interposed links and cams pivotally supported upon the other stationary shaft, and rollers secured to intermediate points in the operating lever arms to engage the surfaces of the cams, said operating lever arms being fulcrumed 110 on said first-named stationary shaft and the movable contact member being yieldingly supported on said contact-bearing member.

3. A circuit interrupter comprising stationary contact members, a movable contact-bearing member, a lever pivoted at an intermediate point and formed into a cam at one end, an interposed link between the opposite end of the lever and the contact-bearing member, a latch adapted to engage the end 125

130

of a cam when the interrupter is closed and means acting on the cam surface for closing the interrupter.

4. A circuit interrupter comprising stationary and movable contact members, a movable contact-bearing member, a lever pivoted at an intermediate point and formed into a cam at one end, an interposed link between the opposite end of the lever and the contact-bearing member, a latch pivotally supported on the contact-bearing member and adapted to engage the end of the cam when the interrupter is closed, and an operating lever provided with a roller for engaging the cam surface in closing the interrupter.

5. In a circuit interrupter, the combination with stationary and movable contact members and an operating lever therefor, of an operating mechanism for connecting the operating lever to the movable contact

members comprising a pivotally mounted contact-bearing member, a plurality of pivotally mounted cam members, links for connecting said cam members to said contact-bearing member, a plurality of levers pivotally mounted upon said contact-bearing member and operatively connected to the said movable contact members, resilient means interposed between said contact-bearing member and said levers for yieldingly supporting said movable contact members, and rollers secured to said operating lever to engage the surface of the said cams.

In testimony whereof, I have hereunto subscribed my name this 23rd day of Dec., 1909.

CURTIS A. TUCKER.
